(57) **CLAIM**

The ornamental design for a truck body tray canopy, as shown and described.

DESCRIPTION

FIG. 1 is a top perspective view of a truck body tray canopy showing my new design;

FIG. 2 is a top plan view thereof;

FIG. 3 is a front view thereof, the rear view being a mirror image thereof;

FIG. 4 is a right side view thereof; and,

FIG. 5 is a left side view thereof.

FIGS. 1, 2, 4, and 5 are shown broken away to indicate indeterminate length.

1 Claim, 4 Drawing Sheets Fig. 1

Fig. 2
